UNITED STATES PATENT OFFICE.

FREDERICK ENGELHARDT, OF ST. JOHNSVILLE, NEW YORK, ASSIGNOR TO
ROTH AND ENGELHARDT, OF ST. JOHNSVILLE, NEW YORK, COPARTNERSHIP.

AUTOPNEUMATIC PIANO-PLAYER.

SPECIFICATION forming part of Letters Patent No. 689,864, dated December 31, 1901.

Application filed March 1, 1901. Serial No. 49,395. (No model.)

To all whom it may concern:

Be it known that I, FREDERICK ENGELHARDT, a citizen of the United States, and a resident of St. Johnsville, Montgomery county, State of New York, have invented certain new and useful Improvements in Autopneumatic Piano-Players, of which the following is a specification.

This invention relates to various improvements in autopneumatic piano-players, and more particularly to means for operating the piano-pedals, either by the perforated music-sheet or by hand, and means for controlling the expression of the instrument.

15 The invention consists in the various features of construction pointed out in the claims.

In the accompanying drawings, Figure 1 is a front view of the piano-player with some of the parts omitted. Fig. 2 is a vertical cross-section mainly on the line 22, Fig. 1; Fig. 3, a detail front view of the air-filter; Fig. 4, a section on line 44, Fig. 3; Fig. 5, a rear view of the piano-player; Fig. 6, a detail of the mechanism for operating the soft piano-pedals; Fig. 25 7, a detail of the mechanism for operating the valve e. Fig. 8 is a detail of the safety-valve and expression-stop; Fig. 9, a plan of the chambered base b³; Fig. 10, an enlarged detail section of the pedal-operating bellows on line 1010, Figs. 9 and 11; Fig. 11, a section on line 1111, Fig. 10; Fig. 12, a plan of the base of chamber d; Fig. 13, a top view of chamber d; and Fig. 14 a cross-section on line 1414, Fig. 9.

35 The letter a represents the frame of the piano-player, and b represents the suction-bellows, operated by treads b' b' and adapted to exhaust the air from the flexible reservoirs or bellows b² b². These reservoirs are connected by the chambered base b³ and exhaust the air from vacuum-chests b⁴ by pipe b⁵. The duct-bridge c, over which the perforated music-sheet passes, communicates with a bellows in the vacuum-chest by pipes c' c² in such a manner that when an opening of the music-sheet passes over a duct in the duct-bridge the air admitted will cause the collapse of the bellows c³. These bellows actuate the levers that in turn actuate the piano-keys, this construction not forming part of my invention

and being illustrated in Patent No. 598,419, issued to F. R. Goolman, February 1, 1898.

In order to filter the air entering the bellows, I interpose between the pipes c' c² a filter or finely-meshed diaphragm c⁴, set into a 55 perforated rail c⁵, that connects the adjoining ends of pipes c' c², Figs. 3 and 4.

The piano and forte pedals of the piano may be operated by the perforated music-sheet or by hand, at the will of the player, the mechanism for operating the pedals by the music-sheet being as follows: The ducts b⁶ of bellows b² connect by cross-duct b⁷ with a duct b⁸, Figs. 9 and 14, that draws the air out of a pair of suction-chambers d and f, by which 60 the piano and forte pedal levers, respectively, are worked. Within the duct b⁷ is placed a spring-actuated valve e, by which communication between ducts b⁶ b⁸, and consequently between chambers d f and reservoirs b², can 65 be cut off. This valve must be opened when the pedals are to be operated by the music-sheet and closed when they are to be operated by hand. The mechanism for setting this valve consists of a push-button e', 70 having cam e², adapted to engage a roller e⁴ of a rod e³. This rod is connected to one end of a lever e⁵, the other end of which is connected by rod e⁶ to a lever e⁷, which is in turn connected to valve e by wire e⁸. When 75 the button e' is drawn out, Fig. 7, a strong spring e⁹ will push rod e³ down to draw valve e from its seat against action of weak spring e¹⁰. When the button e' is pushed in, Fig. 2, the rod e³ will be raised by engagement of the 80 cam e² with roller e⁴, and the valve will be released and will be closed by its spring e¹⁰.

Within the chamber d are arranged a pair of bellows g i, having the usual vents and communicating by tubes g' i' with the duct-bridge c. The bellows g when expanded opens valve g² and closes a vent g³. The valve g² when opened causes communication to be established through pipe g⁴ between suction-chamber d and a small bellows g⁵, so 90 that the latter is collapsed. The bellows g⁵ is provided with a stop g⁶, which will upon the collapse of the bellows bear against the upper bent end of a bar g⁷, pivoted at g⁸ and having a series of notches g¹⁰ g¹¹. The bar g⁷ 95

engages the end of a lever h , pivoted at h' and influenced by a spring h^2 . To the lever h is connected by rod h^3 a lever h^4 , fulcrumed at h^5 , Fig. 6, and engaging with its forked 5 end a vertically-movable rod h^6 , carrying an arm h^7 , that bears upon the soft piano-pedal. As thus far described the lever h will be liberated whenever a perforation of the music-sheet passes over the duct-bridge c above 10 tube g' . To draw the lever h down after being liberated, a perforation must be provided in the music-sheet sidewise and rearward of the first perforation, which second perforation admits air into the tube i' . This air will enter bellows i to expand the same, and thereby open a valve i^2 and close vent i^3 . The valve i^2 establishes communication between suction-chamber d and a bellows i^4 , to which the lever h is connected by rod i^5 . Thus the 15 admission of air into tube i' causes the liberated lever h to be swung upon its pivot h' , so that its free end comes into alinement with the top notch g^{10} of bar g^7 , while it will cause at the same time the arm h^7 to bear upon the 20 soft pedal. After the perforation in the music-sheet has passed the tube g' the bellows g^5 will expand through vent g^8 , so that the bar g^7 is swung toward the right by a spring g^9 , and the lever h thus becomes locked to the 25 notch g^{10} . The soft pedal thus remains depressed until air is again admitted to tube g' , when the bar g^7 is swung to the left to liberate lever h , which will be thrown up by its spring h^2 . The necessary expansion of bellows i^4 is brought about by this spring and can take place, owing to the admission of air 30 through vent i^3 , which will open as soon as the perforation of the music-sheet has cleared tube i' .

If a pianissimo action is desired, the lever h after having been drawn into notch g^{10} is 35 prevented from rising, but is drawn into a lower notch g^{11} of bar g^7 . To this effect a second pair of holes is made in the music-sheet slightly in advance of each other over tubes $g' i'$, so that when air is readmitted to tube g' the bellows i^4 will be further collapsed and will draw the lever h into the lower notch g^{11} . A single perforation over tube g' will 40 again cause the rising of lever h into its normal position in the manner previously described.

The forte pedal of the piano is operated 45 through the suction-chamber f , communicating with bellows f' , which is operated through air-tube f^2 in manner described in relation to the soft pedal. The bellows f' upon collapsing will swing, through rod f^3 , a lever j upon its pivot j' against action of spring j^2 to lower 50 rod j^3 , and thus swing lever j^4 upon its pivot j^5 . This will cause the sliding rod j^6 to lower the arm j^7 , Fig. 2, upon the forte pedal in manner similar to the operation of the soft pedal. The notched bar g^7 and bellows g^5 are not dupli-

cated for the forte pedal, because a double 65 adjustment of the same is not deemed necessary.

As thus far described the two pedals are operated automatically by perforations in the music-sheet. If they are to be operated by 70 hand, the valve e is first closed by button e' , so that the suction is cut off from the chambers d and f , and consequently from bellows i^4 , g^5 , and f' . The levers $h^4 j^4$ are respectively 75 connected by spring-influenced rods $h^8 j^8$ with bell-crank $h^9 j^9$, adapted to be operated by hand. When either of these bell-crank is manipulated, the corresponding lever h^4 or j^4 will be swung upon its pivot to lower the arm h^7 or j^7 upon its pedal. 80

The bellows b^2 are provided with an air-outlet b^9 , Fig. 2, which is normally closed by a spring-valve k , arranged within a valve-box k' , having opening k^2 . When the suction in the bellows becomes excessive and they collapse to an undue extent, a pin k^3 , projecting from the movable section of the same, will raise the valve k off its seat to admit air into the bellows through opening k^2 and the open valve k . 85

In order to enable the operator to control the expression of the instrument by regulating the strength of suction in the bellows b^2 , means are provided for controlling the air admitted through opening k^2 . These means 90 consist of a cover k^4 , arranged above opening k^2 and operated by hand through push-button k^5 and spring-influenced rod k^6 . When the cover k^4 is lowered by button k^5 , the ingress of air through opening k^2 will be checked, 95 so that even if the valve k is opened air cannot freely enter the bellows b^2 . When the cover k^4 is raised off its opening k^2 , the air will flow freely into the bellows upon the lifting of the valve k . 100

What I claim is—

1. In an autopneumatic piano-player, the combination of an arm adapted to engage a pedal, with pneumatic means for operating said arm, a hand-lever for operating said arm 110 independently of the pneumatic means, a valve for cutting off suction from the pneumatic means, and means for operating said valve, substantially as specified.

2. In an autopneumatic piano-player, the combination of bellows having a valve, with means for opening the same upon an excessive collapse of the bellows, a perforated valve-box inclosing the valve, and means for controlling the admission of air to said valve-box, 115 substantially as specified.

Signed by me at St. Johnsville, Montgomery county, State of New York, this 25th day of January, 1901.

FREDERICK ENGELHARDT.
